CAN OPENER AND SEALER

Carl N. Anderson, Staten Island, Clifford J. Den-
nen, Brooklyn, and William A. Graeffinger,
Queens Village, N. Y.

Application September 8, 1950, Serial No. 183,758

6 Claims. (Cl. 30—16)

1

The present invention relates to can openers, and is particularly directed to a combined device for opening and sealing cans or other similar receptacles of the type used in the sale of beer, evaporated milk, cream, oil or other liquids.

In opening cans of the type referred to, it is customary to punch, or otherwise form, a pair of preferably diametrically opposed openings in one end of the can. When the can is tilted, the contents thereof pours through one of these openings, while the other opening provides a vent to permit atmospheric pressure to act upon the surface of the contents.

The primary object of the present invention is to provide a device which is easily and safely carried in the user's pocket, and which may be employed first in forming the customary pair of openings in the top of a can so that the contents may be poured or dispensed, and then may be used to seal the openings so that the contents remaining in the can will be preserved in a usable condition; and in one aspect of the invention the device also includes a bottle opener, formed conveniently as a part thereof, and may be provided with a bottle sealing element.

A specific object of the invention is to provide a combined can opening and sealing device of the character described which is formed of a pair of similar elements flexibly and resiliently connected together and each including a pointed opening forming portion and an opening sealing portion, and wherein the opening forming and sealing portions are related to each other so that the elements must be turned through substantially 180° from their opening forming positions in order to engage the sealing portions in the openings, and turned similarly from the sealed position to permit complete withdrawal of the elements from the can.

Another object of the invention is to provide a combined can opening and sealing device of the character described which is formed of a pair of similar elements, each having a pointed portion for forming the openings in the top of the can and a sealing portion for plugging the openings, and wherein each of the sealing portions is provided with a suitably formed recess or cavity for receiving the pointed end of the other element when the pair of elements are arranged in stored condition so that the device may be safely carried in a user's pocket or otherwise.

A further object of the invention is to provide a combined can opening and sealing device formed of a pair of similar elements, each hav-

2

ing a pointed portion for punching openings in the top of a can and a sealing portion for plugging such openings, wherein each of the sealing portions is provided with a suitably formed recess or cavity for receiving the pointed end of the other element, and wherein the pair of elements are joined together with a flexible and resilient member which continuously urges the pointed elements into the respective recesses or cavities when the elements are in their stored condition.

A still further object is to provide a combined can opening and sealing device of the character set forth, and suited to accomplish the foregoing objects, which is simple and inexpensive in construction, sturdy and compact.

The foregoing and other objectives, features and advantages of the invention will become apparent from the following detailed description of illustrative embodiments thereof, while the new features of combination, construction and operation which are claimed as the invention are set forth more particularly in the appended claims. The detailed description refers to the accompanying drawings which form a part hereof and in which:

Fig. 1 is a detailed elevational view of a combined can opening and sealing device constructed according to an embodiment of the present invention, and with one of the elements forming the illustrated device being shown with the front exposed to view while the rear of the other of the elements is exposed to view;

Fig. 2 is a side elevational view of one of the elements forming the device illustrated in Fig. 1;

Fig. 3 is a horizontal sectional view on an enlarged scale and taken along the line 3—3 of Fig. 2;

Fig. 4 is a horizontal sectional view on an enlarged scale and taken along the line 4—4 of Fig. 2;

Fig. 5 is a horizontal sectional view on an enlarged scale and taken along the line 5—5 of Fig. 1;

Fig. 6 is a detailed side elevational view of the device illustrated in Fig. 1, but with the pair of elements thereof shown in their positions for storage or carrying;

Fig. 7 is a vertical sectional view through a can or similar container showing the use of the device of Fig. 1 in puncturing the top of the can to form a pair of openings;

Fig. 8 is a top plan view of the punctured end of the can;

Fig. 9 is a vertical sectional view, similar to

Fig. 7, but showing the use of the device of Fig. 1 in sealing the openings formed in the top of a can or similar container;

Fig. 10 is a side elevational view, partly broken away and in section, of one of a pair of elements constructed according to another embodiment of the invention, and with the element in condition for forming an opening in the top of a can;

Fig. 11 is a side elevational view of the element of Fig. 10, but in condition for sealing an opening formed in the top of a can;

Fig. 12 is a side elevational view of another embodiment of the invention; and

Fig. 13 is a side elevational view of still another embodiment of the invention.

Referring in detail to the drawings, and initially to Fig. 1 thereof, a can opening and sealing device, embodying the present invention, is there shown and is generally indicated by the reference numeral 10. Such device consists of a pair of elements 11 and 12 connected together by a flexible and resilient member 13.

Each of the elements 11 and 12 includes a pointed portion 14 for puncturing the top of a can and a sealing portion 15, which may be formed integrally with the pointed portion or otherwise joined thereto, and is provided for sealing the opening formed by the pointed portion.

Pointed portion 14 is substantially triangular in cross-section, as indicated in Fig. 4, and is preferably formed with a flat rear surface 16 and a pair of concave front surfaces 17 meeting along a forward spine 18. The side edges of pointed portion 14 flare outwardly from the point to a plane 19 of maximum width, and forward spine 18 also flares outwardly or away from the flat rear surface 16 to a maximum depth or thickness at the same plane 19. From plane 19, portion 14 tapers both in width and thickness toward the root or base 20, and at the base or root 20 the width is substantially less than the maximum thickness at plane 19. Thus, the root or base 20 of portion 14 may be rotated freely within an opening formed by and having the configuration of portion 14 at plane 19.

Sealing portion 15 of each element may be formed integral with pointed portion 14, if of the same material as the latter, or portion 15 may be joined to portion 14 by a reinforcing member 21. In order to improve the engagement of portion 15 within an opening formed in the top of a can, it may be formed of a resilient substance, for example rubber, or of a rigid material with an enveloping layer of a resilient substance. As seen in Fig. 3, sealing portion 15 is also formed with a substantially triangular cross-section, but the front thereof is a flat surface 22 while the rear surfaces 23 are concave and meet at a rear spine 24. As seen in Fig. 2, flat front surface 22 is disposed substantially in the same plane as that of the flat rear surface 16 of portion 14. Sealing portion 15 tapers both in width and thickness from its head or top to its base or root at reinforcing member 21. Each sealing portion 15 is so formed that its cross-section at a plane substantially below the top thereof, that is, along the line 3-3 of Fig. 2, is the same as the maximum cross-section of portion 14 at plane 19, but turned around through 180°.

A cylindrical boss or stud 25 (Fig. 7) extends from the top of sealing portion 15, and a collar 26 is rotatably mounted on stud 25 and formed with an eye 27 to provide for the attachment of

member 13 to elements 11 and 12. Each of the elements 11 and 12 includes a thumb-piece 28, preferably formed integral with boss 25.

Member 13 connecting together elements 11 and 12 may be formed of any flexible and resilient material or construction, and in the illustrated embodiment is shown to include lengths of flexible chain 29 and 30, joined to eyes 27 of elements 11 and 12, and an intermediate spring 31.

Flexible and resilient member 13 not only conveniently joins the pair of elements together to provide a readily usable unit, but also operates to maintain the elements in their nested or stored position which is illustrated in Fig. 6. As seen in Fig. 5, each of the sealing portions 15 is formed with a cavity or recess 32 opening at the base thereof to receive the pointed end of the portion 14 of the other of the elements when the latter are arranged with their portions 14 overlapped and the flat surfaces 16 thereof in confronting relation (Fig. 6). Member 13 is of such length that the spring 31, forming a part thereof, is tensioned when the elements are so arranged, and continuously urges the point of the portion 14 of each element deeper into cavity 32 of the portion 15 of the other of the elements. It is apparent that with the points of elements 11 and 12 shielded or sheathed within cavities 32, the device 10, not only is compact, but may easily be carried in a user's pocket without any danger from the sharp points of the portions 14 thereof.

Referring now to Figs. 7, 8 and 9, the use of device 10 in forming openings in the top of a can 33 to permit the pouring of its contents and in subsequently sealing such openings is there illustrated.

In forming the openings in the top 34 of can 33, either one or the other of the elements 11 and 12 is first held above top 34 with the pointed end of portion 14 thereof engaging the can top at a point adjacent the edge of the latter and with spine 18 disposed inwardly. Pressure is then applied downwardly on thumb piece 28, and the side edges and spine of portion 14 cut into top 34 as the opening forming portion moves into the can. The concave and flaring front surfaces 17 of portion 14 roll the metal at the sides of the opening 35, formed by such cutting action, downwardly into the can so that the edge of the opening, at the upper surface of top 34, are smooth and safe. The opening thus formed has a configuration (Fig. 8) which is substantially similar to the cross-sectional shape of portion 14 at plane 19, that is at its plane of maximum width and thickness. When the element is moved further into the can, so that the base or root 20 of portion 14 enters into opening 35, the element will be free to rotate within the opening. However, the base end of sealing portion 15 will overhang the portion of top 34 disposed at the outside of opening 35 and prevent further downward movement of the element into the can. Thus, sealing portion 15 of element 12 cannot engage in the opening 35 until the element is manipulated to remove the base end of the sealing portion from its position overlying top 34. Since considerable force may be applied to thumb-piece 28 during the forming of opening 35, the sealing portion would normally be moved into the opening by such force were it not for the feature of construction which prevents such excessive movement during the forming of the openings.

After opening 35 has been formed at one

side of top 34, a similar opening 36 may be formed with the other of the elements 11 and 12 at a point diametrically opposed to the location of opening 35. The elements 11 and 12 are then both removed from the respective openings which have been formed, and the can may be tilted to pour its contents from one of the openings 35 and 36, while the other opening serves as a vent to permit atmospheric pressure to act upon the surface of the contents.

If all of the contents of can 33 are not immediately dispensed, device 10 may be used to seal openings 35 and 36 so that the contents remaining in the can are preserved in a usable condition. For this purpose, portions 14 of elements 11 and 12 are extended through openings 35 and 36 until the bases of the sealing portions 15 engage against top 34. Elements 11 and 12 are then rotated through 180° to the positions of Fig. 9, which rotation is not obstructed by connecting member 13 by reason of the rotation of collars 26 on their respective bosses 25. The sealing portions 15, after such rotation, are aligned with the respective openings, and pressure is applied to thumb-pieces 28 to move tapering sealing portions 15 into the openings for plugging or sealing the latter.

The sealing portions 15 may be removed from openings 35 and 36 by lifting or pulling on thumb-pieces 28 until the base of each sealing portion is above the upper surface of top 34, and then rotating elements 11 and 12 through 180° to align each opening forming portion 14 with the respective opening so that the elements may be completely withdrawn from the can. It will be noted that the base or upper ends of opening forming portions 14 underlie the portions of top 34 outside of openings 35 and 36 and would engage against top 34 to prevent complete withdrawal of elements 11 and 12 from the can when the latter are in sealing position. Thus, the elements cannot be blown-out of the can by the accumulation of excess pressure within the latter, for example when the contents of the can is a carbonated beverage, and the possibility of injury to the user by explosively ejected sealing plugs is thereby avoided.

Referring now to Figs. 10 and 11, an element 11', constructed according to another embodiment of this invention, is there shown. It is to be understood that the complete can opening and sealing device having this modified form includes a pair of elements constructed in the manner of element 11' and connected together by a suitable flexible and resilient member such as member 13 heretofore described.

Element 11' includes a portion 14' for punching or forming an opening in the top of a can which is provided with a configuration substantially similar to that of the opening forming portions 14 of the elements 11 and 12 of Figs. 1-9. A shaft 37 extends from the upper end or base of portion 14' and a sealing portion 15', similar in configuration to the sealing portions 15 of Figs. 1-9, is rotatably mounted upon this shaft. A cylindrical boss (not shown) is formed on the upper end of shaft 37 and a collar 26' is rotatable on this boss and carries an eye or similar member for attaching the resilient and flexible connecting member to the element. Finally, a thumb-piece 28' is preferably formed integral with the boss to provide a place for applying pressure when punching openings in the can.

When the sealing portion 15' is in the position illustrated in Fig. 10, that is, 180° out of align-

ment with opening forming portion 14', element 11' is in condition to punch or form an opening in the top of a can, and the sealing portion 15' will not fit into such an opening. After the opening is formed, sealing portion 15' may be rotated 180° into alignment with portion 14', as in Fig. 11, so that the sealing portion fits into the opening and may be urged downwardly to plug the latter. Thus, the entire element need not be rotated to change it from the opening forming position to the opening sealing position, as was the case in the first described embodiment. After the sealing portion 15' has been engaged in the opening, thumb-piece 28' may be grasped and rotated 180° to displace portion 14' out of alignment with the portion 15' so that portion 14' prevents violent ejection of element 11' from the opening as in the first described embodiment. Furthermore, sealing portion 15' is preferably formed with a cavity 32' opening at its lower end (Fig. 10) for receiving the pointed end of the other of the elements when the latter are nested in a manner similar to that described in connection with Fig. 6 so that the nested elements may be carried with safety in a pocket or otherwise.

From the above description it is apparent that can opening and sealing devices constructed according to this invention are simple in structure, nest together into a compact assembly to be carried with safety, and when in use prevent engagement of the sealing portions in the openings while the latter are being formed and also prevent the violent ejection of the elements from the can when the openings in the latter are sealed by the device.

In Figs. 12 and 13 other forms of can openers and sealers embodying the present invention are illustrated, which include a bottle opener formed in the opening forming portion thereof so that such devices are further useful for removing the caps from bottles.

Referring to Fig. 12, a single element 38 is illustrated and shown to include a hole or opening forming portion 39, pointed at one end and tapering toward the other end thereof, and a sealing portion 40 extending from portion 39 and tapering toward the latter. Portion 39 and portion 40 are formed with substantially triangular cross-sections and, as in the previously described forms, the triangular cross-sections are disposed with their apexes in oppositely extending directions. In order to provide a bottle opener, portion 39 is formed with a transverse notch 41 opening at the spine thereof and in back of the plane of maximum cross-section. Notch 41 forms a hooked projection 42 for engagement under the edge of a crown cap, of the type used in sealing bottles, so that the cap may be pried off the bottle.

Element 38 may also be provided with an additional sealing portion 43, at the end of portion 40, to fit into a bottle. Sealing portion 43 is preferably frusto-conical in form so that it may be wedged into the neck of a bottle after the cap has been removed to preserve the remaining contents in usable condition. As in the previously described forms of the invention, an operating member 44, in the form of a thumb-piece, is provided at the end of element 38 remote from the pointed end thereof so that pressure may be applied to member 44 for driving the hole forming portion 39 into the top of a can.

In Fig. 13, an element 45 is shown which includes a hole forming portion 46 pointed at one end and formed with a transverse notch 47 to define a hooked projection 48 for removing bottle

caps. A tapered sealing portion 49 extends from portion 46 to plug an opening formed by the latter. In this embodiment of the invention hole forming portion 46 and sealing portion 49 are both formed with substantially triangular cross-sections which are angularly aligned. As in the element 38 of Fig. 12, element 45 may be provided with a second sealing portion 59 at the end of the sealing portion 49 and formed to fit into the neck of a bottle for sealing the latter after its cap has been removed.

While we have illustrated and described in detail preferred embodiments of the invention, it will be apparent that the new features of construction and combination herein set forth may be embodied in other forms of can opening and sealing devices, and we therefore desire that the invention be accorded a scope fully commensurate with its contributions to the art, which are intended to be defined by the appended claims.

We claim:

1. A combined can opening and sealing element comprising a portion of non-circular cross-sections pointed at one end for forming an opening in the top of a can, and a tapered sealing portion extending from the other end of the first mentioned portion and formed with cross-sections similar to those of said first mentioned portion and turned angularly relative to the latter so that said sealing portion is engageable in an opening formed by said first mentioned portion only after the sealing portion is rotated bodily to register with the shape of such opening.

2. A combined can opening and sealing element comprising a portion of substantially triangular cross-sections pointed at one end for forming an opening in the top of a can and tapering both in width and thickness toward the other end, and a sealing portion extending longitudinally from the other end of the first mentioned portion, said sealing portion being formed with substantially triangular cross-sections turned relative to those of said first mentioned portion and tapering both in width and thickness toward the latter so that said sealing portion is engageable in an opening formed by said first mentioned portion only after it is turned to register with such opening.

3. A combined can opening and sealing device comprising a pair of elements, each of said elements including a portion pointed at one end for forming an opening in the top of a can and a sealing portion extending longitudinally from the other end of said pointed portion for plugging an opening formed by the latter, said elements being formed to nest side by side in oppositely extending directions, and a cavity formed in the sealing portion of each element to receive the pointed end of the first mentioned portion

of the other element when said elements are in their nested positions.

4. A combined can opening and sealing device comprising a pair of elements, each of said elements including a portion pointed at one end for forming an opening in the top of a can and a sealing portion extending longitudinally from the other end of said pointed portion for plugging an opening formed by the latter, said elements being formed to nest side by side in oppositely extending directions, a cavity formed in the sealing portion of each element to receive and shield the pointed end of the first mentioned portion of the other element when said elements are nested, and flexible and resilient means connecting said elements to each other and dimensioned to be tensioned when said elements are nested to urge said pointed ends into the respective cavities.

5. A combined can opening and sealing device comprising a pair of elements; each of said elements including a portion pointed at one end and tapering toward the other end thereof, said portion being formed with substantially triangular cross-sections and having a flat rear face and concaved converging front faces, and a sealing portion extending longitudinally from said other end and being formed with substantially triangular cross-sections reducing in width and thickness toward said first mentioned portion, said sealing portion having a flat front surface substantially co-planar with said flat rear surface of the first mentioned portion and converging concaved rear surfaces so that said sealing portion engages in an opening formed by said pointed portion when said element is turned 180° to register said sealing portion with such opening; a collar rotatable on each of said sealing portions, and a flexible and resilient connecting member attached at its opposite ends to the collars on said pair of elements to permit rotation of the latter without obstruction from said connecting member.

6. A combined can opening and sealing element comprising a hole forming portion pointed at one end, and a sealing portion extending longitudinally from the other end of said hole forming portion, said sealing portion being rotatable about a longitudinal axis to be axially aligned with said hole forming portion in one position for engagement in a hole formed by the latter and to be rotated to a laterally offset position to prevent engagement thereof in such hole.
